UNITED STATES PATENT OFFICE.

LOTTIE MORFORD, OF MIAMI, FLORIDA.

DESIGN FOR A HAT-PIN.

52,669.

Specification for Design.

Patented Nov. 12, 1918.

Application filed July 18, 1918. Serial No. 245,584. Term of patent 3½ years.

To all whom it may concern:

Be it known that I, LOTTIE MORFORD, a citizen of the United States, residing at Miami, in the county of Dade, State of Florida, have invented a new, original, and ornamental Design for Hat-Pins, of which the following is a specification, reference being had to the accompanying drawings, forming a part thereof.

The figure is a perspective view of a design for hat pins, showing my new design.

I claim:

The ornamental design for a hat pin, as shown.

MRS. LOTTIE MORFORD.

Witnesses:

J. C. HANCOCK,
M. L. MORFORD.
